UNITED STATES PATENT OFFICE.

JESSE E. MATEER, OF WILKINSBURG, PENNSYLVANIA, ASSIGNOR TO WESTINGHOUSE ELECTRIC AND MANUFACTURING COMPANY, A CORPORATION OF PENNSYLVANIA.

COIL-TERMINAL.

1,177,346.

Specification of Letters Patent.

Patented Mar. 28, 1916.

Application filed February 7, 1913. Serial No. 746,788.

To all whom it may concern:

Be it known that I, JESSE E. MATEER, a citizen of the United States, and a resident of Wilkinsburg, in the county of Allegheny and State of Pennsylvania, have invented a new and useful Improvement in Coil-Terminals, of which the following is a specification.

My invention relates to binding posts for electrical apparatus and particularly to binding posts adapted for attachment to coils in order to form the terminals thereof.

The object of my invention is to provide a simple and inexpensive binding post or terminal member for a coil that may be secured thereto with a small amount of labor prior to impregnating the coil with an insulating compound, and that is so constructed as to permit of ready and thorough cleaning after impregnation of the coil so that good electrical connections may be made therewith.

A further object is to provide the binding post or terminal member with a shield or guard whereby the insulation of the coil is protected from injury by the means for making connections to the member.

My invention is illustrated in the accompanying drawing, Figure 1 of which is a plan view of a device embodying my invention and applied to a coil, only a portion of which is shown. Fig. 2 is a side view of the device of Fig. 1, the insulation of the coil to which it is applied being shown partially in section.

The present device comprises a frame 1 made from a strip of sheet metal that is folded, and the lower ply of which is straight, while the upper ply is bent to provide an intermediate inverted U-shaped bridge 2 having an aperture for the reception of a clamping bolt 3. A terminal lead 4 of a coil 5, is soldered between the folds of an extension on the frame, substantially as shown in the sketches. In applying the frame 1 to the coil 5, it is held in position upon the first, or primary, layer of insulation upon the coil, and the tape constituting the secondary or subsequent layer of insulation is wound over the flat end portions of the frame in order to secure the same in position. The frame 1 is preferably applied to the coil, in the manner indicated, prior to the impregnation of the coil with a suitable insulating compound, the hardening of which assists in securing the frame

to the coil. The insulating compound is then removed from the upper and lower faces of the bridge to permit of making good electrical connections therewith. An apertured clip 6, that is secured to the end of a conductor to be connected to the terminal of the coil, is placed against the upper face of the bridge, and the clamping bolt 3 is then inserted and a nut 7 is applied to its lower end, for the purpose of clamping the terminal clip tightly against the upper and lower faces of the bridge, a washer 8 being preferably interposed between the clip 7 and the head of the bolt.

By reason of the simplicity of the shape of the terminal device, it may be readily and thoroughly cleaned so that good electrical connections may be made thereto and, since the clamping bolt 3 is not attached to the frame when the coil is impregnated, the cleaning of threaded, or other rough or irregularly surfaced auxiliary parts, is avoided. By reason of the provision of the bridge 2, the connections to the device may be readily made. The lower ply of the frame constitutes a shield or guard that prevents injury to the insulation of the coil that might occur either because of length of the shank of the bolt, or by tools used in making connections to the device.

I claim as my invention:

1. An electrical terminal comprising a metal piece folded to have a base, a two-ply lateral extension at each side of said base, an intermediate portion of one ply that is spaced from the base, and means for connecting a conductor to one of said two-ply extensions.

2. An electrical terminal comprising a single metal piece folded to have a base, a lateral two-ply extension at each side of said base, an intermediate portion of one ply that is spaced from the base, and means for inserting a conductor between the metal parts forming one of the two-ply lateral extensions.

3. An electrical terminal comprising a single metal piece folded to have a base, a lateral two-ply extension at each side of said base, an intermediate substantially U-shaped portion of one ply that is spaced from the base, and means for inserting a conductor between the metal parts forming one of the two-ply lateral extensions.

4. An electrical terminal comprising a single metal piece folded to have a one ply

base, two two-ply extensions thereto, a one
ply intermediate portion that is spaced
from the said one ply base, means for in-
serting a conductor between the metal parts
5 of one of the two-ply extensions, and means
for attaching a conductor to the portion
that is spaced from the base.

5. An electrical terminal comprising a
single metal piece that is folded to have a
10 one ply base, a one ply substantially U-
shaped portion spaced from the base, two
two-ply extensions forming a part of the
base, and means for attaching a conductor
to said U-shaped portion.

6. An electrical terminal for a coil of 15
wire comprising a single metal piece folded
to form a single ply base member having
two-ply extensions for attaching the same
to the coil of wire, and a single ply bridge
portion that is spaced from said base.

In testimony whereof, I have hereunto
subscribed my name this 30th day of Janu-
ary, 1913.

JESSE E. MATEER.
